UNITED STATES PATENT OFFICE.

FRED MATHEWS, OF CHICAGO, ILLINOIS, ASSIGNOR TO CLINTON C. MURPHY, OF CHICAGO, ILLINOIS.

CARLINE.

1,115,080.

Specification of Letters Patent. Patented Oct. 27, 1914.

Application filed July 5, 1913. Serial No. 777,408.

To all whom it may concern:

Be it known that I, FRED MATHEWS, a citizen of the United States, and a resident of the city of Chicago, county of Cook, and 5 State of Illinois, have invented a new and useful Improvement in Carlines, of which the following is a specification.

This invention relates to pressed steel carlines for freight car roofs, and especially 10 to carlines each consisting of a single piece of rolled metal flanged lengthwise and having bifurcated ends which are adapted to be secured to the side plates of a car.

The object of the invention is the production of a light, strong carline adapted both 15 to support the weight of the roof covering and to brace the top of the car against stresses tending to twist or buckle it out of square.

20 A further object of the invention is to strengthen carlines having bifurcated ends at the crotches where the bifurcations join the main carline stems.

With the above objects in view, the invention 25 consists in a pressed metal carline of flanged channel section which decreases in depth and increases in width from the middle toward the ends, the ends thereof being split centrally lengthwise for some distance 30 toward the middle, and spread apart to form straddle leg braces.

The invention also consists in the carline shown in the accompanying drawings, and in the constructional details thereof herein- 35 after described.

What the invention consists in is particularly pointed out in the appended claims.

In the drawings, in which like characters 40 are used to designate the same parts of the carline in the several views, Figure 1 is a top plan view of a carline embodying my invention; Fig. 2 is a half side elevation and half longitudinal section of the same; Fig. 45 3 is an end view of the carline shown in Figs. 1 and 2, drawn to a larger scale; Fig. 4 is a transverse section, drawn to the same scale as Fig. 3, of the carline shown in Figs. 1 and 2, on the line 4—4 in Fig. 1 looking in the direction of the arrows and showing 50 the end of the carline in elevation; and Fig. 5 is a transverse mid-section of the carline shown in Figs. 1 and 2, drawn to the same scale as Figs. 3 and 4.

Referring to the drawings, the carline 11 consists of a metal plate of a length sufficient 55 to span the car from sideplate to sideplate, and of a width such that it may be formed or pressed lengthwise into a channel having the extremities of its side walls 12 provided with lateral top flanges 13. These lateral 60 top flanges are punched with holes 14, 15, through which the bolts for securing the ridge piece and purlins may be passed.

The ends of the carline slope downward from its middle to correspond to the pitch 65 of the car roof. The side walls of the carline decrease in height from the middle toward the ends and the bottom 16 increases in width correspondingly, the result of these variations in dimensions being that the car- 70 line is stiffest in the vertical plane at its middle and in the horizontal plane at its ends. Moreover, the ends of the carline are bifurcated, or horizontally forked, to provide a wide spread lengthwise bearing on 75 the sideplates, whereby the sideplates are braced by the carlines against stresses tending to distort the top of the car out of square.

The end bifurcations or forks 17 are 80 formed by splitting the bottom web 16 in for some distance from the ends. The lengthwise splits or cuts which sever the web terminate at their inner ends in small holes, and the metal surrounding the mar- 85 gins of these holes is flanged up into beads 18 which strengthen the web at these points and prevent it from splitting farther toward the middle after the carline goes into service. The side and bottom walls of the 90 channel at the ends of the bifurcations 17 are bent outward into planes parallel to the sideplates, and the terminal bearing portions 19 thus formed are punched with holes 20 for the bolts which secure the carlines to 95 the sideplates. This construction results in a carline having not only great lateral stiffness at the ends, due to their spreading apart, but also very considerable vertical stiffness at the ends, due to the increased 100 vertical bearing on the carlines formed by the downturned wide end portions of the channel web.

It is evident that the carline shown in the drawings is capable of modifications, and 105 that its modified forms come within the fore-

going description of this invention, and the invention is not restricted to the precise form shown in the drawings.

I claim as my invention:

- 5 1. A carline comprising a rolled-metal channel-shape intermediate portion having its bottom split to form bifurcated ends, said ends having transversely arranged extremities formed by twisting the split bottom 10 tom of the channel at its ends into the plane of its sides walls and bending sidewise the ends of the side walls and twisted bottom portions of the channel.
2. A carline consisting of a single piece of 15 rolled metal of channel form, upwardly arched at its middle, the bottom of the channel being split in from the ends and spread apart to constitute end bifurcations, the side walls of said bifurcations being bent laterally at their extremities into vertical planes transverse to the ends of the carline, and the bottom flanges thereof being twisted down and bent laterally at their extremities 20 into the planes of the extremities of the side walls, the extremities of said bifurcations being adapted to be secured to the side plates 25 of a car.

3. A carline having a web split at the ends and the split portions spread apart, and a bead lining the crotch between said split portions, formed by flanging the portions of the web adjacent to the inner ends of the split. 30

4. A carline having a web split at the ends and the split portions spread apart, said splits terminating in holes in the web at their inner ends, said holes having flanged edges. 35

5. A carline having a web increasing in width from the middle of the carline toward 40 its ends, the ends of said web being split lengthwise, and flanged holes in said web at the inner ends of the splits, said holes forming crotches when said split ends are separated, whereby said carline is strengthened laterally and prevented from splitting lengthwise. 45

Signed at Chicago, Illinois, this 30th day of June, 1913.

FRED MATHEWS.
